UNITED STATES PATENT OFFICE.

JOHN TONNER BRESSLER, OF SHEPARDSTOWN, PENNSYLVANIA.

TRACE CONNECTION.

No. 830,877.

Specification of Letters Patent.

Patented Sept. 11, 1906.

Application filed April 3, 1905. Serial No. 253,554.

To all whom it may concern:

Be it known that I, JOHN TONNER BRESSLER, a citizen of the United States of America, residing at Shepardonstown, in the county 5 of Cumberland and State of Pennsylvania, have invented new and useful Improvements in Trace Connections, of which the following is a specification.

The invention relates to an improvement 10 in trace connections whereby the same may be removably secured to the ends of the usual swingletree.

The main object of the invention is the 15 production of a reinforcing-plate for the trace adapted to be connected with the latter adjacent the slot thereof and constructed to secure the trace to the swingletree against accidental disengagement.

Another object of the invention is to construct the reinforcing-plate to receive the 20 entire strain, whereby the life of the trace is materially increased and all liability of the trace-slot pulling out avoided.

The invention will be described in detail in 25 the following specification, reference being had to the accompanying drawings, in which—

Figure 1 is a perspective view of one end of the swingletree, showing a trace having my 30 improved reinforcing-plate in position. Fig. 2 is a longitudinal central section of the same, the swingletree and retaining-bolt being shown in elevation. Fig. 3 is a vertical section of the same. Fig. 4 is an elevation of the rear 35 end of a trace, illustrating the application of my improved reinforcing-plate. Fig. 5 is a perspective view of my improved reinforcing-plate.

Referring to the drawings, wherein like reference-numerals indicate like parts throughout the several views, 1 represents the ordinary trace adapted for the coöperation with the usual swingletree 2. Each end of the swingletree is provided with a retaining-bolt having 40 a shank 3 of greater transverse length than thickness, the opposite edges of the shank being concaved, as at 4. The free end of the shank is provided with a head 5, comprising an elliptical plate-like member secured 45 near its lower edge to the end of the shank and extending thereabove about at right angles. The trace 1 is provided with the usual slotted opening 6, arranged to receive the bolt-shank 3.

7 represents a reinforcing-plate, preferably coextensive in width with the width of the trace and having endwise-projecting ears 8, through which bolts or rivets 9 are arranged to pass to secure the plate to the trace. The plate is arranged contiguous the trace-slot 6 and is formed with a slot 10 to register with the trace-slot 6. The forward portion of this slot is enlarged, as at 11, while the rear narrowed portion 12 of the slot is of a size as to just receive the shank 3 of the retaining-bolt. 55 The rear wall 13 of the slot 10 is provided with a laterally-projecting lug 14, arranged when the plate is in place to bear against the rear wall of the trace-slot 6, the lug being of a length to project beyond the trace on the side 60 next the swingletree, as shown in Fig. 2. By preference the lug 14 is rounded or convexed in transverse section to arrange for close engagement with the concaved edges 4 of the shank 3. 65

In securing the trace in place the head 5 of the bolt is inserted through the enlarged portion of the trace-slot and plate-slot, the trace being turned until it is at right angles with the shank 3 of the bolt, after which the trace 70 is drawn forward until the narrowed portions of the trace and plate slots engage the shank. The head 5 and the enlargement of the slot are not necessary, however, since the purpose of the invention is as readily obtained by the 75 omission of the head on the swingletree and securing my plate provided with a slot of a thickness corresponding to that of the ordinary swingletree now used.

Draft upon the traces will cause one edge 80 of the shank 3 to bear against the lug 14 of the plate, whereby the trace is relieved of all wear and strain and its life materially increased and any danger of accident through breakage of the parts avoided. 85

The reinforcing-plate may be of any thickness desired, though it is preferably so constructed as to adapt it for the particular use desired, the plates for light harness being of less thickness than those for heavy harness. 90

It will be noted that the lug 14 of the plate receives all the wear and strain incident to draft on the traces and that the walls of the slot and plate will prevent any wear upon the walls of the trace-slot. 100

Having thus described the invention, what is claimed as new is—

A reinforcing-plate for trace-eyes compris-

ing a plate of single thickness and designed to be secured on the outer side of the trace, said plate being formed with a slot to register with the eye in the trace and having a projecting lug extending from the rear wall of the slot, said lug being of greater length than the thickness of the face and designed to bear against the rear wall of the eye in the trace, the wall of the slot in the plate forward of said lug being free of projection beyond the

plane of the plate, whereby the trace-eye wall is free to yield independently of the plate to permit the insertion of the swingletree-hook.

In testimony whereof I affix my signature in presence of two witnesses.

JOHN TONNER BRESSLER.
